UNITED STATES PATENT OFFICE.

DONALD J. CAMPBELL, OF MUSKEGON HEIGHTS, MICHIGAN.

PISTON-RING PLIERS.

1,57,082.

Specification of Letters Patent.

Patented Oct. 19, 1915.

Application filed October 16, 1913. Serial No. 795,593.

To all whom it may concern:

Be it known that I, DONALD J. CAMPBELL, a citizen of the United States of America, residing at Muskegon Heights, in the county of Muskegon and State of Michigan, have invented certain new and useful Improvements in Piston-Ring Pliers; and I do hereby declare the following to be a full, clear, and exact description of the invention, such as will enable others skilled in the art to which it appertains to make and use the same.

My invention relates to improvements in piston ring pliers, and its object is to provide a convenient tool for removing and replacing piston rings, and to provide the same with various new and useful features hereinafter more fully described and particularly pointed out in the claims, reference being had to the accompanying drawings representing an embodiment of my invention, in which:

Figure 1 is a perspective view of a device embodying my invention with a piston ring held thereby; Fig. 2 an enlarged detail of one of the jaws of the device; Fig. 3 an elevation of the jaws of the same; Fig. 4 a plan view somewhat enlarged, of the jaws arranged as shown in Fig. 1; Fig. 5 a diagrammatic view of a portion of the device engaged with a ring before expanding the same; Fig. 6 the same with the ring expanded; and Fig. 7 the same as Fig. 6, with the device adjusted for a wider ring.

Like numbers refer to like parts in all of the figures.

1 represents a pair of handles for manually operating the device. These handles are divided at 2 and oppositely prolonged from the pivot to form a pair of jaws which do not cross each other but swing apart as the handles are forced toward each other. Each jaw is provided with a lug 4 on its end adjacent to the inner surface of the jaw and beveled to fit the beveled end of the ring where the same is cut apart. On each jaw is mounted a flexible stop plate extending opposite the lug and adapted to engage

the respective upper and lower sides of the ring which terminate in acute angles. These 50 spring stops normally are spaced apart from the lugs to adapt the device to the wider piston ring as indicated in Fig. 7, and are adjusted closer to the lugs by thumb screws 6 for the narrower rings as in Figs. 5 and 6. 55 The type of ring for which this device is adapted is shown at 7, which is a single integral ring of resilient material severed diagonally to the axis, the ends where so severed being normally spaced apart, as indicated in Fig. 5, a sufficient distance to receive the lugs 4 therebetween when the same are brought close together by swinging the handles 1 away from each other.

In operation, when the lugs are placed 65 between the severed ends of the ring and sprung apart the acute angles of the ring will engage between the lug and the stop and by forcing the jaws apart the ring may be sprung apart or expanded sufficiently to 70 be placed upon a piston or removed therefrom, and when so expanded the ring can be carried by the tool to any desired place.

What I claim is:

1. Piston ring pliers, comprising a pair 75 of jaws movable toward and away from each other, lugs on the ends of the jaws and at adjacent sides thereof, and adjustable stops adjacent to the lugs to engage the side of the ring.

2. Piston ring pliers, comprising a pair of pivoted handles, jaws projecting from the handles and moved apart by the handles when the same are moved toward each other, inclined lugs on the ends of the jaws and at 85 adjacent sides of the same, stops opposite the lugs to engage opposite sides of the ring, and screws to adjust the stops toward and away from the lugs.

In testimony whereof I affix my signature 90 in presence of two witnesses.

DONALD J. CAMPBELL.
